WILLIS S. FARNSWORTH, OF SAN FRANCISCO, CALIFORNIA, ASSIGNOR TO COIN
CONTROLLED LOCK CO., OF SAN FRANCISCO, CALIFORNIA, A CORPORATION
OF CALIFORNIA.

COIN-CONTROLLED LOCK.

1,120,294.

Specification of Letters Patent.

Patented Dec. 8, 1914.

Application filed February 8, 1912. Serial No. 676,448.

To all whom it may concern:

Be it known that I, WILLIS S. FARNSWORTH, a citizen of the United States, residing in the city and county of San Francisco and State of California, have invented new and useful Improvements in Coin-Controlled Locks, of which the following is a specification.

This invention relates to a coin-controlled lock, and particularly pertains to mechanism for controlling the operation of the lock by means of coins, slugs or other tokens.

It is the object of this invention to provide a lock which is so constructed and arranged that it can be operated only by the depositing of a proper coin or token.

A further object is to provide a coin-controlled device which is adapted to be applied to the ordinary cylinder locks now generally in use, with but slight alteration of the lock structure.

Another object is to provide a coin-controlled lock, in which the use of dogs, trip levers, pawls, or other tripping and releasing mechanisms are dispensed with, thereby producing a coin-controlled lock, which is simple in construction and efficient and reliable in operation.

Still another object is to provide a coin-controlled lock, which is adapted to be readily set for coins of various denominations, and which is so arranged that the coin employed in operating the lock will be exposed when the bolt of the lock is in its locked position; and which is not liable to become choked by the insertion of additional coins.

Other objects will appear in the following specifications.

The invention consists of the parts and the construction and combination of parts, as hereinafter more fully described and claimed, having reference to the accompanying drawings, in which—

Figure 1 is a rear view of the lock with casing removed, showing the bolt in its retracted position and locked against movement. Fig. 2 is a similar view showing the bolt in its advanced position. Fig. 3 is a detail showing the bolt as retracted, and showing the coin in the position assumed following its deposit. Fig. 4 is a similar view, illustrating the manner in which the coin is employed as a means for advancing the bolt and showing the bolt in its ad-

vanced position. Fig. 5 is a horizontal section on the line X—X, Fig. 1. Fig. 6 is a detail vertical section of a cylinder lock. Fig. 7 is a detail vertical section on the line Y—Y, Fig. 3.

In the drawings, A represents a face plate or escutcheon which is designed to be placed on the outer face of the door or casing to which the lock is to be applied; this escutcheon plate being formed with a slot 2, 60 for the reception of coins, opening to a coin chute 3 mounted on the back of the escutcheon A.

A base plate 4, on which the lock mechanism is supported, is mounted on the back of the escutcheon A and is formed with an outwardly projecting flange 5 which is formed with a vertical slot 5' arranged to receive the forward end of a bolt 6. The bolt 6 parallels the plate 4 and is spaced 70 for a short distance therefrom, as shown in Fig. 5, and is supported and guided at its rear end upon a bracket 7 which extends beneath the lower edge of the bolt and is slotted to extend on each side of the bolt, as 75 shown in Fig. 7. A pin 8 is positioned on the bolt 6 to strike the bracket 7 on its forward face to limit the rearward movement of the bolt.

Mounted on the base plate 4, above the bolt 6, is an ordinary cylinder lock of any suitable type, which is here shown as consisting of a barrel B mounted in a cylindrical casing C and having the usual loose pins or tumblers D and E which are actuated by the insertion of a key F in the key-hole G, extending longitudinally through the barrel B.

A bit, or projecting pin 9, is suitably attached to the inner end of the barrel B adjacent the base plate 4, and is normally positioned to extend at an angle into a peculiarly shaped notch or slot 10 formed in the upper edge of the bolt 6. The rear wall of the slot 10 extends at an angle the full depth of the slot, while the forward wall of the slot is broken to form a horizontal shoulder 11 about midway of the depth of the slot, as shown in Fig. 1. Pivotedly mounted on the bit 9 is a link or actuator 12 which extends parallel with the bolt 6 and is supported at its outer end in a guide 13 carried on the bolt. The outer end of the actuating link 12 is bent inwardly at right angles to form a finger 14 which ex- 100 105 110

tends through a slot or perforation 15 formed in the bolt 6, as shown in Fig. 5.

Mounted on the bolt 6 and extending toward the base plate 4 is a pair of spaced pins 16-17; the pin 16 being positioned on the bolt adjacent its lower edge and a short distance forward of the point where the finger 14 extends through the bolt, and the pin 17 is positioned adjacent the upper edge of the bolt near its forward end. Mounted on the base plate 4 adjacent the pin 16 is a pin 18, which extends across the space between the base plate 4 and the inner face of the bolt 6, and terminates adjacent the latter, as shown in Fig. 5.

As a means for preventing the bolt 6 being advanced by the rotation of the lock barrel B, a hump 19 is formed on the lower edge of the bolt rearward of and adjacent the bracket 7, in such position as to engage the bracket 7 when the bit 9 is brought to bear against the forward edge of the slot 10, as indicated in dotted lines in Fig. 1. The pressure of the bit 9 against the forward edge of the slot 10 causes the hump 19 to tend to ride over the supporting edge of the bracket 7, which action, however, is prevented by means of the shoulder 11 abutting against the lower edge of the advanced bit 9, thus preventing the forward movement of the bolt.

The slot 10 is formed in the bolt 6 in such position and of such width as to limit the movement of the bit 9, and thereby hold the barrel B in such position as to dispose the pins E out of alinement with the loose pins D mounted in the casing C, as shown in Fig. 1; the pins E bearing against the walls inside the cylinder C. When the parts are in this position, the key F is blocked against removal, as is well known in locks of the Yale type, in which the key can only be withdrawn when the keyhole and key stand in a certain position, usually vertical, to dispose the pins E in the barrel B in alinement with the pins D in the cylinder C, and allow the pin E to move up into the recesses holding the pins D as they ride over the serrations on the key F when the latter is inserted or withdrawn.

From the foregoing it will be seen that when the bolt 6 is in the retracted position, shown in Fig. 1, it cannot be advanced, nor can the barrel B of the lock be turned sufficiently far to admit of the withdrawal of the key F therein; the hump 19 acting in conjunction with the shoulder 11 to block the bolt 6 against forward movement, which blocking of the bolt causes the forward edge of the slot 10 to limit the movement of the bit 9 on the barrel B.

The coin chute 3 leads to and terminates above the space between the bolt 6 and the base plate 4, as shown in Figs. 1 and 2, in such manner that when a coin is discharged

therefrom, the coin will fall between the pins 17-18 and the finger 14 and be supported upon the pins 17-18, when the bolt 6 is in its retracted position, as shown in dotted lines in Fig. 3.

70

In the operation of this invention, a coin 20 of the proper value, or a suitable token, is inserted in the slot 2, from which it passes down the chute 3 and is delivered behind the bolt 6 only to come to rest on the respectively movable and fixed pins 17-18, as just described; the pins 17-18 being spaced apart according to the diameter of the coin to be used. The key F is then operated to rotate the barrel B to turn the bit 9 and the link 12 thereon in the direction of the arrow in Fig. 3. The link 12 is of such length that the finger 14 thereon will strike the edge of the coin 20 at a point below its middle, before the lower edge of the bit 9 engages the bolt 6. By this arrangement the movement of the bit 9 is transmitted through the link 12, coin 20 and the pin 17 to project the bolt 6 to its advanced position. The engagement of the finger 14 on the link 12 with the coin 20, before the bit 9 reaches the shoulder 11, allows the hump 19 to ride over the bracket 7; the bit 9 entering the lower portion of the slot 11 when the rear end of the bolt is moved upward by the hump 19 passing over the bracket 7. When the bolt 6 reaches its advanced position and pressure is released on the key, the coin 20 is released from the pin 18 and drops upon the pin 16, and is then supported on the pin 16 on the bolt 6 and against the rear face of the flange 5, as shown in dotted lines in Fig. 4, in which position it remains as long as the bolt is advanced; the coin being exposed to view through a perforation 21 formed in the plates A and 4. The key F may now be removed from the barrel B, as the pins D and E will be in alinement. Should a second coin be deposited in the chute 3, either before or after the advancing of the bolt 6, it will strike the coin 20 and will pass behind the bolt 6 over the finger 14, as indicated in dotted lines in Fig. 3, and will fall into any desired receptacle below the lock. When the bolt is retracted, which is done by re-inserting the key F in the barrel B and turning the latter in the direction of the arrow in Fig. 4, to cause the bit 9 to engage the rear edge of the slot 10, the pin 16 will be withdrawn from beneath the coin 20 and the latter will be allowed to drop into any suitable receptacle, not shown.

100

The movement of the bolt 6 is retarded by means of a plate spring 22 which is attached to the bolt 6 and bears against the under side of the bracket in such manner as to normally retain the bolt in its lowermost position and at the same time prevent too easy movement thereof.

130

Means are provided for indicating the number of operations of the bolt 6, which are here shown as consisting of a register 23 of any suitable description, the operating lever 24, which is engaged by a slot 25 formed in the lower edge of the bolt 6; the register 23 operating in the well-known manner to indicate the number of times the lock has been used.

10 Having thus described my invention, what I claim and desire to secure by Letters Patent is—

1. In a lock, the combination of a casing, a sliding bolt, a coin chute, a pin on the casing and a complementary pin on the bolt arranged to intercept a coin when the bolt is in one position, a key operated member, a bit projecting from said member, an actuator operated by said bit and arranged when 20 the key is turned in one direction to encounter the coin to shift the bolt, a projection on the bolt, a bracket on the casing with which said projection engages, and means on the bolt coöperating with said bit for preventing said projection from passing said bracket when no coin is inserted.

2. In a lock, the combination with a key and a key operated member, of a bolt provided with a notch, means for supporting a 30 coin on the bolt, a bit on the key operated member, a link on said bit to engage the coin to advance the bolt, and means on the bolt coöperating with said bit to prevent movement of said bolt when no coin is supported by the bolt, said means comprising a shoulder on one side of said notch.

3. In a lock, the combination of a bolt, a key operated bit, means for supporting a coin on the bolt, means on said bit for engaging the coin to advance the bolt as the bit is advanced, a projection on the bolt, a casing for the bolt, a bracket on the casing engaging said projection and preventing unauthorized advancement of the bolt, and 45 means on the bolt whereby the movement of the bit will be limited to prevent the disengagement of said projection and said bracket when a coin is not supported by the bolt.

4. In a lock, the combination of a bit, a key for rocking said bit, a bolt having a notch engaging said bit to prevent turning of the bit when no coin is inserted, pins on said bolt for supporting a coin, a link on said bit arranged to engage the coin to advance the bolt when the bit is rocked, means for limiting the movement of the bit to prevent the removal of the key and the advancement of the bolt, when a coin is not supported on the bolt, consisting of a hump 60 on the bolt, a bracket engaged by said hump, and a shoulder formed in the notch engageable with the underside of the bit.

5. In a lock, the combination of a bit, a key for rocking said bit, a bolt having a notch, pins for supporting a coin on the bolt, a link on said bit arranged to engage the coin to advance the bolt when the bit is rocked, means for limiting the movement of the bit to prevent the removal of the key 70 and the advancement of the bolt, when a coin is not supported on the bolt, consisting of a hump on the bolt, a bracket engaged by said hump, and a shoulder formed in the notch engageable with the underside of the 75 bit, and means operated by the bolt for registering the number of operations of the bolt.

6. In a coin controlled lock, the combination of a bit, a key for rocking said bit, a bolt having a notch, a shoulder on one side of said notch engaging said bit, pins for supporting a coin on the bolt, and a link on said bit arranged to engage the coin to advance the bolt when the bit is rocked, and means coöperating with said shoulder for limiting the movement of the bit to prevent the removal of the key and the advancement of the bolt when a coin is not supported on the bolt, said last named means comprising 90 a projection on the bolt.

In testimony whereof I have hereunto set my hand in the presence of two subscribing witnesses.

WILLIS S. FARNSWORTH.
